LOCOMOTIVE DRIFTING MECHANISM

Frank W. Corcoran, Los Angeles, Calif.

Application December 21, 1935, Serial No. 55,607

2 Claims. (Cl. 121—137)

The invention relates to locomotives operated with superheated steam and the object is to provide means associated with the valves and cylinders whereby to prevent carbonization 5 therein when the engine is "drifting," i. e., running with the throttle valve closed.

Under such conditions air drawn into the cylinders causes combustion with the lubricating oil due to the excessive heat of the cylinder walls. If the engine is allowed to run for any 10 length of time the cylinders and valves become dry which in turn results in broken rings and an overhauling job which is very expensive.

Apparatus has heretofore been devised to overcome the above objectionable conditions. However, such apparatus relied upon suction or 15 vacuum created in the engine cylinder to cause the same to function, i. e. supply steam to the valve chest and cylinder while the engine is drifting.

Although said devices serve their intended purpose (to a certain degree), they fail to function quickly enough to prevent damage to the valves and pistons. It is therefore another object 20 of the present invention to provide an apparatus of the character stated which will instantly function (upon closing of the throttle) and supply steam in measured quantities in relation to the piston displacement.

I accomplish the above and other objects by 25 means of the apparatus described herein, and shown in the accompanying drawing, in which,

Fig. 1 is a fragmentary side elevation of a locomotive showing the improved drifting mechanism applied thereto, parts being shown in 30 section.

Fig. 2 is a view taken approximately on line 35 2—2 of Fig. 1, parts being broken away and shown in section.

Fig. 3 is a diagrammatical plan view.

Fig. 4 is a horizontal section taken on line 40 4—4 of Fig. 1.

Fig. 5 is a detail section taken on line 5—5 of Fig. 2.

Referring more specifically to the drawing 45 10 designates the locomotive cylinder in which operable a piston 11 having a rod 12 that is interconnected to a usual cross head 13 slidable between guides 14. Formed integral with or mounted on the cylinder is a steam chest 15 in which is operable a usual piston valve 16, said chest communicating with the cylinder through ports 17.

It will be understood that the valve is actuated to open and close port 17 through any con-

ventional valve gear not shown. Communicating with the steam chest is a conduit 18 that extends therefrom to a superheater (not shown) located forwardly of the boiler tubes within the usual shell.

Positioned above the valve chest is a member generally designated at 20 which forms part of the apparatus of the present invention, i. e., for admitting saturated steam into the steam chest and cylinders for the purpose heretofore set forth.

Slidably mounted in a bore formed in the lower portion of member 20 is a small piston valve 21 that alternately opens and closes ports 22 communicating with drums or chambers 23 formed in the upper portion of said member. Arranged midway of the ends of the member (see Fig. 4) is a plate 24 that separates the chambers and extending through said plate is a port 25 which in turn communicates with the boiler indicated at B through a pipe 26 to a point thereon for the delivery of saturated steam between the valve heads as shown in Fig. 1.

Formed in bottom wall of the member 20 and communicating with the bore is a duct 27 which in turn communicates with the main steam chest midway of its ends through a suitable fitting indicated at 28.

Secured to valve 21 and extending therefrom through a stuffing box 29 and guide 30 is a rod 31 which in turn is pivotally connected as indicated at 32 to a link 33. The opposite end of the link engages a stud 34 projecting from a block 35 that slidably engages an arcuate link 36. Projecting from the arcuate link through an opening formed in a bracket 37 is pin 36^a 35 which serves as a pivot point for said link.

Connected to stud 34 is a hanger 38 the upper end of which is connected to an arm 39 that is secured to a rock shaft 40.

Secured to the rock shaft and depending therefrom is an arm 41 having a bifurcated end that engages a pin on the outer end of a rod 42. Rod 41 extends through a guide 43 carried by a cylinder 44 in which is operable a piston 45 secured to said rod between the piston and guide 43 is an expansion coil spring 46 that serves to lower the block 35 on the link 36 for a purpose hereinafter described.

Communicating with the cylinder adjacent 50 its rear end wall and leading therefrom to the superheated steam conduit 18 is a pipe 47. Threaded in the rear wall of cylinder 44 is an adjusting screw 48 whereby inward movement of

the piston may be varied which in turn through the linkage will influence travel of valve 21.

In other words it will be seen that by limiting inward movement of the piston the stroke of valve 21 may be varied whereby the volume of steam admitted to cylinder may be regulated according to the speed and displacement of piston.

One end of a link 49 is connected to the lower end of the arcuate link 36 while its opposite end is connected to the upper end of a lever 50.

10 Lever 50 is pivotally mounted as indicated at
15 51 on a supporting member 52 that is preferably
51 mounted on the upper cross head guide, the low-
er end of said arm being connected to the cross
15 head 13 through a link 53.

From the foregoing, it will be seen that, as long as the throttle is opened (or partially so), steam will be admitted through pipe 47 to the cylinder 44 forcing the piston therein forwardly 20 against the spring 46 and through the linkage above referred to cause the valve 21 to remain stationary as no movement will then be imparted thereto, altho the link may be swung back and forth during movement of the cross head. Under 25 conditions when the throttle valve is closed while the engine running or drifting steam from the pipe 18 will be cut off causing the piston 45 to move rearwardly through reaction of the spring 46. It will be understood that the spring 30 is of sufficient tension to cause operation of valve 21 before steam in pipe 47 is depleted or before the throttle is entirely closed.

Recoil of the spring 46 under these conditions causes block 35 to be moved downwardly on the arcuate link 36 by arm 39, 41 and the hanger 38 to a point thereon which will cause valve 21 to be reciprocated during movement of the cross head 13 through the lever 50.

During travel of valve 21, communication will be first established between ports 22 and 25 causing the chambers 23 to become alternately charged with steam through pipe 26. Steam thus admitted to the chambers is then released, and passes through the duct 27 thence into the steam chest 15.

In other words when one chamber is being filled or charged the other is discharging.

in measured quantities, in relation to the piston displacement, is delivered to the steam chest and cylinder also that no steam will enter the same, except during reciprocation of valve 21, thus preventing any starting of the locomotive after closing of the throttle valve.

It will also be apparent that by employment of the apparatus above described saturated steam in sufficient but not in excessive volume is supplied to cylinders while the engine is drifting.

Referring to Fig. 3, two members **20** operable by a single cylinder **44** through the ports above described is herein shown, it being understood that one member with pipes leading therefrom may be employed if desired.

I claim:

1. In a superheated steam locomotive including a steam chest and cylinder a body member having steam receiving chambers therein mounted on and having ports communicating with the steam chest, and steam receiving chambers a valve operable in said body member for opening and closing the ports therein for admitting saturated steam into the valve chest, means for operating said valve when the throttle is closed including an arcuate link, a piston, a cylinder and a spring normally holding said valve inactive, and means for actuating said valve from a moving part of the locomotive operable upon closing the throttle valve. 30
  2. In a superheated steam locomotive including a steam chest and cylinder, a body member having steam receiving chambers therein mounted on and having ports communicating with the steam chest and steam receiving chambers, a valve operable in said body member for opening and closing the ports therein for admitting saturated steam into the valve chest, means for operating said valve when the throttle is closed including an arcuate link, a piston, a cylinder and a spring normally holding said valve inactive, and linkage connecting said piston with said valve and to the cross head of the engine, whereby upon the closing of the throttle steam will be admitted to the valve chests and cylinders of the locomotive in advance of its depletion from the main throttle valve. 35 40 45
